Primary Examiner—Paula A. Mortimer[57] **CLAIM**

The ornamental design for a chair clip, as shown and described.

DESCRIPTION

FIG. 1 is a front perspective view of a chair clip showing my new design;

FIG. 2 is a front perspective view thereof;

FIG. 3 is a top plan view thereof;

FIG. 4 is a front elevational view thereof;

FIG. 5 is a bottom plan view thereof; and,

FIG. 6 is an end elevational view thereof, the opposite end is a mirror image.

The broken line showing of the chairs in FIG. 1 is for illustrative purposes only and forms no part of the claimed design.
